UNITED STATES PATENT OFFICE

143,931

DESIGN FOR A TOOL HANDLE

William H. Odlum, Wilmette, Ill., assignor to Duro Metal Products Company, Chicago, Ill., a corporation of Illinois

Application July 20, 1945, Serial No. 120,829

Term of patent 14 years

(Cl. D93—4)

To all whom it may concern:

Be it known that I, William H. Odlum, a citizen of the United States, residing at Wilmette, in the county of Cook and State of Illinois, have invented a new, original, and ornamental Design for a Tool Handle, of which the following is a specification, reference being had to the accompanying drawing, forming part thereof.

Fig. 1 is a plan view of a tool handle embodying my new design;

Fig. 2 is another plan view of the same after

it has been turned on its longitudinal axis forty-five degrees from the position of Fig. 1;

Fig. 3 is an elevational view of the tool shank-receiving end of the handle; and

Fig. 4 is an enlarged elevational view of the butt end thereof.

I claim:

The ornamental design for a tool handle, as shown.

WILLIAM H. ODLUM.
